UNITED STATES PATENT OFFICE.

MAX N. AARON AND SAMUEL N. GOODMAN, OF PHILADELPHIA, PENNSYLVANIA, ASSIGNORS, BY DIRECT AND MESNE ASSIGNMENTS, TO FRIEDBERGER-AARON MANUFACTURING COMPANY, OF PHILADELPHIA, PENNSYLVANIA, A CORPORATION OF PENNSYLVANIA.

DESIGN FOR LACE EDGING.

41,514.

Specification for Design.

Patented June 20, 1911.

Application filed February 24, 1911. Serial No. 610,630. Term of patent 7 years.

To all whom it may concern:

Be it known that we, MAX N. AARON and SAMUEL N. GOODMAN, citizens of the United States, residing at Philadelphia, county of Philadelphia, and State of Pennsylvania, have invented a new, original, and ornamental Design for Lace Edging, of which the following is a specification, reference being had to the accompanying drawings, which form a part thereof.

The figure is a plan view of a portion of the edging embodying our new design.

We claim:

The ornamental design for a lace edging as shown.

In testimony of which invention, we have hereunto set our hands, at Philadelphia, on this 17th day of February, 1911.

MAX N. AARON.

SAMUEL N. GOODMAN.
